UNITED STATES PATENT OFFICE.

FREDERICK S. DUESENBERG AND AUGUST S. DUESENBERG, OF DES MOINES, IOWA.

VALVE-GEAR.

1,244,481.

Specification of Letters Patent. Patented Oct. 30, 1917.

Original application filed April 14, 1913, Serial No. 760,851. Divided and this application filed August 13, 1914. Serial No. 856,543.

To all whom it may concern:

Be it known that we, FREDERICK S. DUESENBERG and AUGUST S. DUESENBERG, a subject of the Emperor of Germany and a citizen of the United States, respectively, and both residents of the city of Des Moines, county of Polk, and State of Iowa, have invented certain new and useful Improvements in Valve-Gears; and we do hereby declare

5 that the following is a full, clear, and exact description of the same, reference being had to the accompanying drawings, and to the numerals of reference marked thereon, which form a part of this specification.

10 This invention relates to an improved valve gear particularly well adapted for use on internal combustion engines, although, of course, not limited to such, being a divisional application of our co-pending application for patent for "internal combustion engines", filed April 14th, 1913, Serial No. 760,851.

15 Much of the inefficiency of gas engines now upon the market wherein puppet valves are used, may be traced to the valve action, owing to the fact that at high speed the valves do not seat perfectly. Furthermore, due to the fact that the valves are in a position on the cylinder subject to the heat of 20 the explosion, they become overheated and stick open, and then too they become fouled with carbon forming a product of the combustion. In internal combustion engines heretofore constructed an exceedingly large 25 clearance space has been practically unavoidable where it is desired to use large valves, and this is particularly true of the well known type of T-head motor. Another disadvantageous feature in prior constructions 30 has been that the fuel entering through the valves has been required to flow a considerable distance before reaching the ignition means and the time required for such travel is an important factor when the motor is 35 operating at high speed. It is almost essential that the fuel be ignited immediately upon its admission after closure of the admission valve, so closely and quickly do the events in the cycle of operation take place.

40 Another defect in multi-cylinder engines has been the complication of valve mechanisms with an inadequate lubricating system therefor, but which, in our invention, is a feature 45 of the valve gear which has been carefully 50 considered.

It is an object of this invention to construct an upright internal combustion engine with valves opening horizontally into a small clearance space above the cylinders thereof, and with an improved valve gear 60 for actuating the valves in proper sequence.

It is also an object of this invention to construct an internal combustion engine provided with water jacketed valves opening laterally into a small clearance space above 65 the cylinders and with mechanism for actuating said valves incased within the engine, concealed from view, and protected, as well as insuring a silent running engine.

70 It is also an object of this invention to construct an internal combustion engine wherein a valve gear is provided for the laterally movable valves embracing a plurality of rocker arms, one for each valve and actuated by a suitable cam shaft, and with a 75 lubricating means associated with the valve gear and operated from a part thereof to admit oil to the wearing surfaces of the gear.

75 It is a further object of this invention to construct a valve gear for the valves of an 80 internal combustion engine wherein certain members of the valve gear mechanism serve to convey lubricating oil therethrough, and with means associated with said member to intermittently communicate with the oil carrying 85 means to feed the oil to other parts of the gear.

It is finally an object of this invention to provide in combination with an internal combustion engine of novel construction, a 90 particularly efficient valve gear incased within the walls of the engine and well lubricated at all points, and connected to be driven from the crank shaft of the engine.

95 The invention (in a preferred form) is illustrated in the drawings and hereinafter more fully described.

In the drawings:

Figure 1 is an end elevation of an engine embodying our invention, and with the cover 100 for the gear case removed.

Fig. 2 is a vertical section thereof.

Fig. 3 is a left side elevation broken away and partly in section.

Fig. 4 is an enlarged fragmentary detail 105 section taken on line 4-4 of Fig. 2.

Fig. 5 is an enlarged top plan view of the crank case with the cylinders removed and the connecting rods in section.

Fig. 6 is an enlarged fragmentary vertical 110

section taken through the top of the engine, illustrating the mounting of one of the valves therein.

Fig. 7 is an enlarged detail partly in section and partly in elevation of the lower end of one of the rocker arms and the cam shaft for actuating the same.

Fig. 8 is a detail section taken on line 8-8 of Fig. 7.

10 Fig. 9 is a detail section taken on line 9-9 of Fig. 7 with parts omitted.

Fig. 10 is a fragmentary rear view of the upper end of the rocker arm.

As shown in the drawings:

15 The crank case 1, is constructed of cast metal in any suitable manner, and is provided, if desired, with transverse interior webs, on which, and at the ends of the crank case is journaled the crank shaft 2, which 20 may be constructed, of course, as usual, the construction in this particular as to the bearings for the crank shaft, varying with the size of the engine, and the number of cylinders employed. Said crank case is provided on its right side with a removable side plate to afford access to the interior of the crank case, and at its top is provided with a suitably apertured and seated base plate 4, which may be integral with the remainder 25 30 of the crank case, if desired, and upon which seat and are rigidly secured the respective cylinders A, B, C, and D, which are rigidly secured in place thereon in the usual or any suitable manner.

35 Said cylinders, as shown, are each provided at the top with a relatively narrow and upwardly extending combustion chamber 5, which communicates in the top of the cylinder and extends substantially parallel 40 to the crank shaft, and the top of the cylinder is so shaped as to afford a slight clearance above the piston when at the end of its exhaust, and its compression strokes.

Each of said cylinders is water jacketed, 45 and the water jacket may be afforded by coring the cylinder when cast or in any suitable manner. Conveniently, on the right or ignition side of said engine, a removable plate 6, affords one wall of the water jacket, 50 and by removal permits access to the interior of the water jacket for inspection or repair. For the remaining portion of the periphery of the cylinder, and extending well into the head thereof above and around 55 the combustion chamber, the water jacket is preferably cored in the metal, as indicated by 7, and if desired, a cover plate 8, may be provided to afford access to the interior of the water jacket by its removal.

60 Inlet and exhaust ports of relatively large size are provided at the left side of the combustion chamber and are closed by mechanically operated puppet valves 9 and 10, respectively, each of which is rigidly secured 65 on a stem 11, which extends through a suit-

able bearing sleeve 12, seated in a suitable bore in the side of the engine cylinder adjacent the combustion chamber, as shown in Figs. 4 and 6. Secured on the outer end of the valve stem 11, is a stop 13, between which and the wall of the cylinder engages a pushing spring 14, said spring acting at all times to hold its valve closed. As shown, an oil aperture is provided in the bearing sleeve 12, for each valve stem, and opens 70 upwardly at the outer side of the sleeve, as indicated by 15, in Fig. 6, whereby the oil (converted practically to a vapor by the splash lubrication hereinafter described) finds access to the stem to lubricate the same 75 at all times.

The inlet valves are arranged in pairs in adjacent cylinders. In the construction shown, in which four cylinders are used, the inlet valves 9, of the cylinders A and B, are 80 closely adjacent each other, and between the exhaust valves for said cylinders, and in the cylinders C and D, the same arrangement is maintained, so that the inlet manifold X, indicated in dotted lines in Fig. 3, 85 requires but two branches for a four cylinder engine, one of the branches opening directly to the valves 9, in the cylinders A and B, and the other of the same opening directly to the valves 9, in the cylinders C and 90 D, while the exhaust manifold Y, as indicated also in dotted lines in Fig. 3, is provided with four branches which lead from the respective exhaust valves and upwardly 95 therefrom.

100 The right side of the combustion chamber, or that opposite the valves, is bored to afford relatively large threaded openings therein, one directly opposite each of the valves and threaded thereto are closures 16, for the exhaust valves, and 17, for the inlet valves, the latter of said closures being apertured to permit the insertion of a spark plug 18, in close proximity with the inlet valve and directed toward the axis 110 thereof, as shown in Fig. 4. Said closures, upon removal, permit ready removal of the respective valves through the opening therefor, and permit the hand to be inserted into the cylinder to permit the cylinder to 115 be thoroughly cleaned and any carbon therein removed, when desired, and without necessitating removing the cylinders from the crank case.

Connected with the respective cranks of 120 the crank shaft, are connecting rods 20, of course, one for each cylinder, and each engaged with a piston 21, which may be constructed in the usual or any suitable manner. The crank shaft is provided on its outer 125 end with a gear wheel 22, which meshes with a larger gear wheel 23, secured on a cam shaft 24, and affording a two to one drive therefor, said cam shaft being journaled in the crank case extending longitudi- 130

nally at the rear side thereof, and provided with suitable cams for actuating the respective valves. Said gears are, of course, incased to permit the same to run in oil.

- 5 Journaled above the cam shaft, is a tubular shaft 25, journaled on which are rocker arms 26, each made up of abutting flat levers with reinforced edges and having a cylindrical extension integrally formed a
 10 short distance below the middle thereof to permit said rocker arms to be journaled on the shaft 25, one rocker arm for each inlet valve, and one for each exhaust valve, the upper, longer end of each of which extends
 15 into engagement with the outer end of the corresponding valve stem, as shown in Figs. 2 and 3, while the lower end thereof, which may be provided with a suitable anti-friction shoe 27, extends into bearing against
 20 the cam shaft in position to be engaged and actuated by the appropriate and corresponding cam thereon, so that when the shorter end of said lever is actuated by the cam, the upper end is thrown inwardly with greater
 25 velocity, instantly affording full opening of the valve actuated thereby, which, upon release of said rocker arm by said cam, is instantly closed by the action of the valve spring 14.
 30 The bearing on said tubular shaft 25, for the rocker arm, is supplied with force feed lubrication; so also is the lower end of said rocker arm, so that the friction occasioned by the engagement of said rocker arms by
 35 the respective cams, is reduced to a minimum. For this purpose, as shown, an oil compartment is provided in the bottom of the crank case, an inner floor or bottom 28, being provided therein, as shown in Fig. 2,
 40 the space beneath said inner floor affording an oil well or container, and communicating therewith at the bottom, and cored in the side of the cylinder, is a casing 29, providing a cylindric bore or chamber therein in
 45 open communication with said oil compartment at its inner side.

A pump barrel 30, is held in position over said chamber 29, by a bracket 31, extending inwardly from the walls of the crank case, 50 and slidable through said barrel 30, is a plunger 32, normally impelled upwardly by a spring 33, wound therearound, the upper end of said plunger bearing beneath a cam 34, secured on said cam shaft 24. A pipe 35, 55 communicates in the bore of the tubular rocker arm shaft 25, and also with said pump chamber 29, so that the interior of said shaft is at all times filled with oil. At each bearing of the rocker arms on said shaft, an oil port 36, is provided for the rocker arm, and as clearly shown in Fig. 7, and connected in the hub of each of the rocker arms is a pipe or tube 37, which leads 60 downwardly therefrom along the inner face of the rocker arm and delivers oil to the

bearing plate 27, on the end of the rocker arm engaged by the cam.

Of course, the bearing plate or shoe 27, may be adjustably secured upon said rocker arm if desired, and also at the upper end adjustable means may be provided to vary the bearing of said arm on the valve stem. Conveniently also, and particularly in the larger engines, an anti-friction roller may be provided on the lower end of the rocker to minimize friction from engagement of the cam with the rocker for actuating the latter. This, in engines of smaller size, is, however, not necessary. A crank 38, on the end of the crank case, is connected to a valve element 39, journaled in the bottom of the crank case for controlling the level of the oil therein, but inasmuch as this mechanism forms no part of the present invention, the details of construction and operation thereof are not entered into here. 70 75 80 85

When the engine is assembled and properly adjusted a left side closing plate 40, is secured in place, as shown clearly in Figs. 1 and 2, to entirely inclose the rocker shaft, rocker arm, and all the operating or moving parts of the engine, the joints of course being preferably gasketed or ground to afford a tight fit and prevent leakage of oil. 90 95

The operation is as follows:

The entire left side of the crank case being open, the oil within the crank case is driven into a fine mist almost vaporous in character, which, at all times, bathes all the operating parts of the engine, affording efficient lubrication. The oil falling upon the valve stem 11, and passing into the oil port 15, in the sleeve 12, insures thorough lubrication for, as well as serving to cool the valve stem, and also lubrication for the point of engagement of the upper end of the rocker arm, with the end of the valve stem. 100

Owing to the hollow tubular shaft 25, through which oil is conveyed and on which the rocker arms are journaled, the bearings for the rocker arms are readily lubricated, so that minimum friction and resistance is afforded for the operation of the valves. The cam 34, on the cam shaft 24, serves to operate the plunger oil pump, pumping oil through the pipe 35, which communicates with the interior of said tubular shaft 25. Of course, the small pipes 37, mounted on each of the rocker arms, serve to intermittently receive oil from said tubular shaft 25, and feed the same to the contacting surfaces of the wear plates 27, and cams upon the cam shaft. The cycle of operation is as usual in four cylinder four stroke internal combustion engines. However, as the inlet manifold X, has but two branches of equal length, owing to the inlet valves of each pair of cylinders being provided adjacent each other, it follows that an equal

supply of hydro-carbon mixture is provided for each cylinder, thus affording uniform and efficient operation.

The shape and position of the respective 5 relatively high but narrow combustion chambers 5, arranged above the axis of each cylinder, is such that the inlet and exhaust valve of each cylinder at one side of the combustion chamber, are brought into very 10 close relation with the ignition means, so that when the charge is compressed the ignition terminals are practically at the center of the compressed mixture. This is important, as it affords uniform and complete 15 combustion of the entire charge almost instantaneously. Not only does the arrangement of the valves and spark plug add greatly to the efficiency of the engine, but a further and important advantage is found 20 in the readiness with which the valves and the exterior of the cylinders may be inspected. The closures 16 and 17, may be removed when desired, thereby permitting the removal and replacement of the valves there-through, and as well the combustion chamber 25 may be cleaned when desired through said apertures.

Of course it is to be understood that details of construction will vary through a 30 considerable degree with the size of the engine. For example, it is desirable to provide rollers on the cam ends of the rocker arms for large units, and in some instances force feed lubrication may be used elsewhere 35 than as shown and described. We have, of course, shown a preferred form of our invention, but we do not purpose limiting the patent granted otherwise than necessitated by the prior art.

40 We claim as our invention:

1. In a device of the class described a 45 multiple cylinder internal combustion engine embracing cylinders, pistons, a crank shaft, a continuously driven cam shaft, rocker arms journaled above the cam shaft with the shorter arms thereof directed into 50 position for direct contact with the cams thereon, and the longer ends directed into position for valve actuation, inlet and exhaust valves arranged transversely the axis of the cylinder and at the same side of the cylinder, each provided with spring pressed stems extending into position each for direct contact with the rocker arms, and 55 means mounted on the rocker arms and movable therewith for lubricating the bearings for the rocker arms and the points of engagement of the cams thereon.

2. In a device of the class described a 60 multiple cylinder engine, inlet valves arranged in pairs for adjacent cylinders, an exhaust valve adjacent and parallel therewith for each cylinder, said valves acting transversely the axis of the cylinder, rocker 65 arms journaled at the side of each cylinder

for characteristically actuating the valves, a crank case open at the top at one side into which said rocker arms extend, end walls formed on the engine, and a cover plate attached thereon inclosing said rocker arms. 70

3. In a device of the class described the valves and valve stems, and mechanisms for operating the same embracing a bearing sleeve for each valve stem ported to permit admission of oil to the stems, springs engaged on each sleeve and against the ends of the valve stems and acting to hold the valves seated, cam actuated rocker arms extending outwardly along each side of each cylinder with the longer arms thereof contacting 75 a valve stem, and the shorter ends thereof in position to be contacted by the appropriate cam on the cam shaft, said mechanisms being in open communication with the crank case for splash lubrication, and a 80 cover plate wholly inclosing said mechanisms within the casing of the engine.

4. In a device of the class described the combination with an internal combustion engine and its crank case extended at one 85 side of the engine and open for its entire length, of a valve gear therefor comprising a cam shaft in said crank case driven from the crank shaft of the engine, a tubular shaft mounted above said cam shaft, a plurality of rocker arms journaled on said tubular shaft, with the lower ends thereof extending inwardly into the crank case through the open portion thereof, ports in 90 said shafts to permit oil to flow from the interior of said shaft to the bearing for said rocker arms, valves mounted at the upper ends of the cylinders adapted to be actuated by said rocker arms, and a pipe mounted on each rocker arm leading from the 95 bearings in said rocker arms to the point of contact of the rocker arms and cam shafts to admit lubricating oil thereto.

5. The combination with an internal combustion engine and its crank case, of valves 100 communicating laterally in spaces above each of the cylinders of the engine, rocker arms projecting into said crank case for opening said valves, springs for returning said valves to closed position, a cam shaft in 105 the crank case driven from the crank shaft of the engine for actuating said rocker arms, an oil pump, mechanism on said cam shaft for operating the same, communication between said oil pump and the supports for 110 said rocker arms, whereby oil is forced into the interior of said supports and fed outwardly therethrough into the bearings of each of said rocker arms, and a pipe secured 115 on each of the rocker arms and movable therewith adapted to transmit oil from said supports to said mechanism on the cam shaft.

6. In a valve gear for internal combustion engines a stationary tubular shaft, a plu- 120

rality of rocker arms journaled thereon, ports in said shaft and rocker arms adapted to register with one another, a cam shaft for actuating said rocker arms, a pipe connected rigidly on each of said rocker arms and movable therewith and communicating with the port in the rocker arm and at its other end adapted to discharge oil received from said tubular shaft through the registering ports to the contacting surfaces of the rocker arm and cam shaft, and valves for the engine adapted to be actuated by said rocker arms.

In testimony whereof we have hereunto subscribed our names in the presence of two 15 subscribing witnesses.
